UNITED STATES PATENT OFFICE.

RICHARD E. JONES, OF HAGERSTOWN, MARYLAND.

SELF-ADJUSTING SPRING-HINGE.

1,139,296.

Specification of Letters Patent. Patented May 11, 1915.

Application filed December 9, 1909. Serial No. 532,165.

To all whom it may concern:

Be it known that I, RICHARD E. JONES, a citizen of the United States, residing at Hagerstown, in the county of Washington 5 and State of Maryland, have invented a new and useful Improvement in Self-Adjusting Spring-Hinges, of which the following is a specification.

This invention relates to self-adjusting 10 spring hinges, especially adapted to be used in connection with cold storage doors the object being to provide a hinge which is so constructed that compression will be obtained on the gasket of the door so as to 15 form an exceedingly tight joint.

Another object of my invention is to provide a hinge which is exceedingly simple and cheap in construction and one which is very 20 strong and durable, the parts being so mounted that the door will be supported in such a manner that all danger of the same 25 become jammed is prevented.

A further object of my invention is to provide a hinge which is so constructed that 25 a door carried thereby will be held within the door frame under tension at all times in such a manner that the gasket around the door will be compressed by the pressure of the spring so as to insure an air tight joint.

With these objects in view, my invention 30 consists in the novel features of construction, hereinafter fully described, pointed out in the claim and shown in the accompanying drawings, in which:

Figure 1 is a front elevation of my improved self-adjusting spring hinge showing the same in position on a cold storage door and frame. Fig. 2 is a horizontal section through the door and frame taken above the 35 hinge, the cylinder of the hinge being broken away. Fig. 3 is a vertical section taken on the line 3—3 of Fig. 2.

Referring to the drawing A indicates the door frame of a cold storage building or 40 room, B the door for closing the same and C my improved hinge for supporting the door within the frame so that the same will be held therein under the tension of the spring at all times as will be hereinafter 45 fully described.

In carrying out my improved invention, I employ a cylindrical casing D adapted to be embedded in the wall of the building or room under the facing of the door frame in 50 alinement with an opening formed in the door frame through which extends the col-

lar E of a facing plate F which is secured in position on the door frame by lag bolts G so as to hold the same firmly thereon and said collar is provided with an annularly reduced portion E' adapted to fit within the open end of the cylinder D so as to form a snug joint and for securing the collar within the cylinder, I provide the cylinder D with a threaded bore D' in which is mounted 60 a set screw D² adapted to engage the collar as clearly shown.

Extending through the face plate F and collar E is a stem H of a U-shaped head I, the arms of which are apertured as clearly 70 shown through which is adapted to extend a pintle bolt J on which is pivotally mounted the eye K of a strap L which is provided with a series of openings through which lag 75 bolts L' are adapted to pass for securing the same to the outer face of the door and this strap may be formed of any design desired. Arranged on the pintle bolt J under the eye K is a washer M forming a bearing for the eye so as to allow the eye to turn freely on 80 the bolt in order to allow the door to swing easily.

The inner end of the stem H is provided with a threaded bore H' over which is arranged a washer N which is secured in position by a set screw N' and surrounding the stem H between the washer N and the end of the collar E is a coil spring O the tendency of which is to draw the stem inwardly so that the head will be drawn tightly 90 against the face plate at all times and it will be seen that by this construction the gasket on the door will be compressed when the door is closed so as to form an air tight joint.

From the foregoing description, it will be seen that I have provided a self-adjusting spring hinge which is so constructed that the same can be readily attached to a cold storage door and frame so as to hold the door tightly closed within the frame under the tension of the springs of the hinge whereby the packing material carried by the frame and door will be compressed when the door is closed.

Having thus fully described my invention, what I claim as new and desire to secure by Letters Patent, is:

In a device of the kind described, the combination with a cylindrical casing, of a plate 110 having a collar the inner end of which is reduced and fitted into the end of the casing,

a stem extending through the plate and collar, and bifurcated at its outer end, its inner end having a threaded bore, a washer arranged upon the end of stem, a screw for holding the same in place, a spring surrounding said stem and bearing upon said washer and reduced end of collar, and a

strap adapted to be secured to a door said strap being pivotally connected to the bifurcated outer end of stem as set forth.

RICHARD E. JONES.
